REFRIGERATING APPARATUS

Glenn F. Zeilhoefer, Bloomington, Ill., assignor to
 Williams Oil-O-Matic Heating Corporation,
 Bloomington, Ill., a corporation of Illinois

Application March 29, 1937, Serial No. 133,519

1 Claim. (Cl. 62—119)

This invention relates to improvements in the absorption type of refrigerating apparatus in which a solvent such as dimethyl ether of tetra-ethylene glycol, or a similar type of chemical 5 forms a solution with a refrigerant such as dichloromonofluoromethane, or a similar type of chemical in an absorber, the solution passed into a heater or still wherein the refrigerant is released or boiled off the solution and delivered to 10 a condenser, collected as a liquid in a receiver, and delivered to an evaporator from which the gaseous refrigerant is returned to the absorber while the solvent of the solution from which the refrigerant has been separated in the heater re- 15 turns to the absorber. This invention relates more particularly to the method and means, when the evaporator employed is of the flooded type, of returning from the evaporator such particles of the solvent which invariably are carried over with the gaseous refrigerant into the 20 evaporator.

The single figure of the drawing is a diagrammatical representation in elevation of an evaporator of the flooded type with the connections to 25 the condenser or receiver and absorber such as employed in an absorption type of refrigerating apparatus as described above. Other elements of such a system do not form a part of this invention and, therefore, it is not thought necessary 30 to illustrate them. The evaporator illustrated is employed for the purpose of cooling water or brine, as less heat transfer surface is required in this method of cooling than in the method using a dry expansion type of evaporator.

35 In an absorption refrigeration apparatus or unit using dimethyl ether of tetraethylene glycol as a solvent, and dichloromonofluoromethane as the refrigerant, for an example, which operates at a temperature of 235° F. in the heater, and 40 with a pressure of twenty-eight pounds gauge in the heater, the solvent carried over with the gaseous refrigerant as it leaves the heater is approximately 0.1%. This solvent is then carried over in solution with the refrigerant from the condenser to the low side. When the refrigerant vaporizes in a flooded type of evaporator, essentially all the solvent carried over remains in the 45 evaporator. In due time, the unit becomes inoperative due to this accumulation of solvent, unless 50 provision is made for the return of the solvent from the evaporator to the absorber.

This difficulty is not encountered in a dry expansion type of evaporator because the velocity of the refrigerant vapors carries the solvent 55 through the evaporator back to the absorber

even though there is a considerable rise between the point at which vaporization starts in the evaporator and the point of inlet to the absorber.

The purpose of this invention is to provide means of returning the solvent from the flooded 5 evaporator rapidly enough to maintain satisfactory concentration of refrigerant in the evaporator.

Referring to the above example, where the liquid dichloromonofluoromethane in the condenser of this type of absorption refrigeration unit is 95° F. and the saturated refrigerant temperature in the evaporator is 40° F., the refrigeration required to cool the liquid refrigerant from the temperature in the condenser to the 15 evaporator temperature of 40° F. is approximately 14 B. t. u.'s per pound, or approximately 13.6% of the total refrigeration effect produced in the evaporator by the vaporization of one 20 pound of refrigerant.

This cooling of the refrigerant may be effected within the evaporator or may be effected by pre-cooling the refrigerant before it enters the evaporator. In pre-cooling the liquid refrigerant from the condenser by the vaporization of refrigerant 25 taken from the evaporator, it is possible to have a flow of refrigerant from the evaporator equivalent to approximately 10% of the flow of refrigerant from the condenser to the evaporator. Consequently, if the refrigerant from the condenser has 0.1% solvent and the refrigerant taken 30 from the evaporator for pre-cooling the liquid refrigerant has 1% solvent, the amount of solvent taken with the refrigerant for pre-cooling is equivalent to the amount of solvent carried into 35 the evaporator with the refrigerant from the condenser when the rate of flow of refrigerant from the evaporator to the pre-cooler is 10% of the rate of flow from the condenser to the evaporator. Since concentrations of solvent in the refrigerant of as much as 3% or 4% is not objectionable for operation of the flooded low side, it follows that it is not necessary to use more than one-third to one-fourth of the refrigerant necessary 40 to pre-cool the liquid refrigerant to the evaporator temperature. It is, therefore, contemplated in accordance with this invention to feed the refrigerant from the evaporator through a fixed orifice into a pipe connected to the absorber and around which is a concentric pipe 45 through which flows the liquid refrigerant from the condenser to the evaporator, in a counterflow to the gaseous refrigerant in the inner pipe.

With these and other objects in view, reference is made to the accompanying drawing which ill- 55

lustrates a preferred embodiment of this invention, with the understanding that detail changes may be made without departing from the scope thereof.

- 5 The evaporator **E** indicated in longitudinal vertical central section is preferably in the form of a cylinder provided with convex end closures 2 and 3. A vertical partition 4 separates the end closure 2 from the body of the evaporator. 10 A float valve chamber 5 is supported on the opposite end closure 3 with a float-operated valve to maintain the liquid level, as shown by the dotted lines, in the evaporator and is connected by pipes 6 and 7 to the upper and lower sides of 15 the evaporator respectively.

The pipe 8 leads the fluid to be cooled into the top of the space between the end closure 2 and partition 4. The partition 4 supports the ends of a row of horizontal pipes 9 which extend to 20 a point adjacent the opposite end closure 3 and are then bent to return in parallel spaced-apart relation to the partition 4. The pipes 9 are arranged to extend normally above the level of the liquid refrigerant in the evaporator, as shown, 25 by the dotted lines, with the respective ends opening through the partition 4 into the space between the end closure 2 and the partition 4 and each is preferably provided with thin equally-spaced-apart radiation plates or fins 10, as shown. 30 A horizontal partition 11 is arranged between the end closure 2 and the partition 4 between the openings of the upper and lower rows of the pipes 9, whereby the liquid from the pipe 8 is caused to circulate through the pipes 9 in 35 the gaseous refrigerant. It is preferable to arrange two similar rows of pipes 12 and 13 below the pipes 9 with partitions 14 and 15 similar to partition 11 between their respective openings into the chamber between the end closure 40 2 and the partition 4, whereby the fluid is caused to circulate through the liquid refrigerant within the evaporator **E**. The space below the partition 15 is connected to a pipe 16 for conducting the cooled fluid to its destination.

45 A pipe 17 leads the liquid refrigerant from the receiver or condenser of the apparatus, not shown, to the float chamber 5 and a pipe 18 leads the gaseous refrigerant evaporated at the liquid level in the evaporator to the absorber of the apparatus, not shown.

50 This invention contemplates the prevention of such solvent as is invariably carried over from the heater or still with the refrigerant into the evaporator from collecting therein and eventually rendering the evaporator inoperative by providing at the bottom of the evaporator a small orifice or bleeder 19, preferably of adjustable size, which opens into a pipe 20 leading to the absorber of the apparatus, not shown. The pipe 20 is arranged in the form of a goose-neck 55 21 below the under-side of the evaporator and may be termed a semi-flooded container, as the refrigerant with particles of solvent enters this portion through the orifice 19.

The size of semi-flooded pipe must be small enough to carry proper velocities of gaseous refrigerant so as to sweep the solvent liberated in pipe 20 back to the absorber; also sufficiently large to provide for the delivery of the required amount of the refrigerant-solvent mixture to maintain satisfactory equilibrium of solvent and refrigerant in evaporator. 5

Sufficient head must be maintained between low point of the goose neck of the semi-flooded pipe and liquid refrigerant level in the evaporator to insure adequate flow of refrigerant-solvent mixture from the evaporator to semi-flooded pipe against back pressure built up by frictional resistance of gaseous refrigerant in the semi-flooded 10 pipe. 15

The warm liquid refrigerant from the condenser effects vaporization of the refrigerant in pipe 20 affording a quite definite and controlled amount of heat for this purpose and at the same 20 time conserving the refrigeration effect.

This invention contemplates providing an enlargement 22 of the pipe 17 through which the pipe 20 passes from a point adjacent the bottom of the evaporator, a sufficient distance to produce the desired effect. The liquid refrigerant is conducted from the enlarged portion 22 of the pipe 17 adjacent the evaporator by a pipe 23 leading to the float chamber 5, and the refrigerant is conducted from the float chamber 30 to evaporator **E** by pipe 7.

This same type of device may be used in conjunction with a compressor to return oil from a flooded low side to the crank case of a compressor. 35

What I claim is:

In an absorption refrigerating apparatus including a horizontal cylindrical evaporator of the flooded type provided with a float valve, for controlling the level of the liquid refrigerant 40 therein, within a chamber, a pipe for leading the liquid refrigerant from the condenser to the float valve chamber, a pipe for leading the gaseous refrigerant from the evaporator to the absorber, and a bleeder orifice opening through the bottom 45 of the evaporator into a pipe depending therefrom to form a liquid trap and that is to then lead to the absorber, said latter pipe on leaving the evaporator passing through an enlarged substantial section of the pipe leading the liquid 50 refrigerant to the float valve chamber, the size of the bleeder and the length of said enlarged section so related that the solvent carried over from the heater with the gaseous refrigerant and passing through the float valve is removed from the bottom of the evaporator with a sufficient portion of the liquid refrigerant to be volatilized in passing through the said enlarged section and the solvent separated therefrom swept into the 55 absorber. 60
